DISCONNECTING SWITCH

William H. Lindae, St. Louis, Mo.

Application March 30, 1936, Serial No. 71,665

11 Claims. (Cl. 200—162)

This invention relates generally to electrical switching apparatus and has more particular reference to disconnecting switches of the swingable blade type for engaging or disengaging fixed or stationary poles or contact-members for, respectively, making or breaking the electrical circuit.

It is known that contact resistance is a function of pressure and not of area; and that by decreasing the contact area to a point or a line and increasing the pressure, greater contact efficiency is obtained.

Nevertheless, high contact pressures produce difficulty in switch operation. Moreover, the limited contact surface which accompanies point contact area necessarily occasions relatively high temperature at the point of contact, which must, of course, be dissipated through the metal-work of the switch structure.

20 My present invention has for its prime object the provision of a disconnecting switch employing a point contact between the blade and the pole or poles of the switch and having superior current carrying characteristics obtained by employing low resistance contact elements of unique formation in conjunction with ample thermal radiating surface for dissipating heat from the switch structure.

My invention has for another object the provision, in a disconnecting switch of the type stated, of a novel structure for the connection of the switch elements to the bus or line, so that, contrary to present general practice, it is unnecessary to carefully prepare the contact surfaces in order to prevent a high resistance therebetween, the contact parts in my construction being, with ease and facility, merely clamped together without prior preparation for securing ample and adequate current carrying capacity with minimum resistance losses.

40 My invention has for a further object the provision, in a disconnecting switch of the type stated, of a simple and rugged latch construction, having a minimum number of parts and hence inexpensive in manufacture and reliable in operation.

My invention has for a still further object the provision of a disconnecting switch of which both the moving and stationary operative parts 50 may be readily disassembled from the base or frame of the switch without necessitating the dismantling of the switch base from its support or from the associated busses and line structures, a feature found to be particularly useful and 55 economical in the installation and maintenance

of both indoor and outdoor disconnecting structures.

My invention has for a still further object to generally improve upon, and reduce the cost of manufacture, installation, and maintenance of, 5 disconnecting switches of the type stated.

And with the above and other objects in view, my invention resides in the novel features of form, construction, arrangement, and combination of parts presently described and pointed out 10 in the claims.

In the accompanying drawings (two sheets)—

Figure 1 is a top plan view of a single pole single throw disconnecting switch embodying one form of my invention, the insulation supports 15 and the bus-bars or line terminal connections being shown by dot-dash lines;

Figure 2 is a side elevational view, partly broken away and in section, of the switch of Figure 1;

Figure 3 is an enlarged fragmentary side elevational view of the latch end of the swingable blade and its associated stationary contact-post, other parts of the switch structure being omitted and the blade being shown in opened position, 25 that is, disengaged from the contact-post;

Figure 4 is a fragmentary sectional view through the latch-structure, taken approximately along the line 4—4, Figure 2;

Figure 5 is a disassembled perspective broken 30 view showing one of the blade-arms, the latch carrying bracket, and one of the filler-plates associated therewith;

Figures 6, 7, and 8 are, respectively, enlarged fragmentary side elevational views of modified 35 forms of the contact post constructions;

Figure 9 is an enlarged detail side view of one of the bell-crank latch members;

Figure 10 is a reduced side elevational view of a single pole double throw disconnecting switch 40 embodying another form of my invention;

Figure 11 is a top plan view of a single pole single throw multiple contact disconnecting switch also embodying my invention, this form of the switch being similar to that of Figure 1, the 45 supporting structure and terminal connections thereof being omitted;

Figure 12 is a reduced side elevational view of a so-called gang-operated out-doors disconnecting switch embodying a modified form of my improved switch construction; and

Figure 13 represents a series of fragmentary sectional views of various modified forms for providing low resistance contact areas in the switch structure.

Referring now more in detail and by reference characters to the drawings, which illustrate practical embodiments of my invention, A, in Figures 1 and 2, designates a disconnecting switch 5 of the front connected type especially, though not exclusively, adapted for indoor or switchboard mounting, 1 and 2 being the pair of spaced insulator stands or supports common in such constructions, as well known to those skilled in the 10 art.

My new switch structure includes a pair of spaced base or terminal plates 3, 4, each, respectively, mounted on a corresponding insulator stand 1, 2, by suitable fastening means, as bolts 15 5, 6.

The plates 3, 4, which are each formed of a suitable conductive material, as copper or the like, are respectively provided with an extension 6, which projects rearwardly, as it may be said, 20 in the case of the plate 3 and forwardly for the plate 4, from the corresponding insulator support 1, 2, each extension 6 being provided with an aperture 7 for receiving a suitable fastening element in the form preferably of a bolt 8, by 25 means of which there may be attached to the plate 3, or 4, the corresponding terminal of the circuit served by the switch, as, for example, the bus-bars 9, 10, or the like.

Disposed in each extension 6 around its aperture 7, is a series of, in the present instance three, contact plugs 11 of relatively small diameter or area and formed of a suitable highly conductive material whose oxide is preferably also conductive, as silver or the like.

35 The plugs 11 are welded or otherwise attached to, or inset into, one or both faces of the extension 6 and project outwardly therefrom a small distance, so that, when the particular bus-bar is mounted on the terminal-plate, the plugs 11 will 40 be compressed therebetween for establishing a substantially small contact area under heavy pressure, a type of electrical joint construction having the characteristics of high current carrying capacity with low resistance losses.

45 In contrast to the usual and, so far as I am aware, heretofore necessary, laborious work and painstaking care taken to insure perfectly flat contact surfaces between the conducting members to be connected, it will be seen that, in my construction, a highly efficient electrical joint connection may, with the greatest of ease and facility and with minimum expenditure of time and labor, be readily formed in the field during the installation of the switch or other structure.

55 Threaded or otherwise fixed at their respective lower ends into, and upstanding from, the respective plates 3, 4, are preferably cylindrical conducting posts 12, 12', each provided at its upper end with a switch-contact 13 having a ball-like, spherical, or other suitable arcuate surface conformation. In practice, the contact-member 13 is mounted on a reduced upwardly presented section 14 of the particular post and secured thereto for axial or rotatable shiftable movement 60 by means preferably of a round-head machine screw 15, as shown.

The arcuate or spherical members 13 preferably form the stationary contacts of the switch A, as will presently more fully appear, and it is 70 to be particularly here pointed out that the members 13 are each provided with a silver surface coating or otherwise formed, as will presently appear, for reducing their surface resistance losses.

Further upstanding from the plate 3 intermediate the posts 12, 12', and having foot-lugs 16

engaged by means of suitable fastening elements in the form of screws 17 with the plate 3, is a hinge-post 18 carrying at its upper or free end a transverse pintle or fulcrum-pin 19.

Upstanding from the plate 4 adjacent to, but disposed outwardly from, the post 12', similarly having lugs 20 engaged by means of screws or other suitable fastening elements 21 with the plate 4, is a latch-post 22 carrying a forwardly and downwardly turned detent or bill 23 and having a pair of opposing lateral lugs or ears 24 disposed flush with its upper or free end.

The swingable contact-member of the switch A includes a pair of laterally spaced registering parallel members in the form preferably of bars 25 having plane surfaces and constructed of suitable conducting material, as copper or the like, the bars 25 being pivotally mounted, each intermediate its ends, on the respective opposite ends of the fulcrum-pin 19, which for such purpose, projects suitably from the respective opposite sides of the post 18.

The bars 25 are adapted at their relatively short rear end-portions for simultaneously embracing and flatwise slidably engaging and disengaging diametrically opposite points on the arcuate or spherical member 13 on the post 12 and at their relatively long front end-portions for simultaneously embracing and flatwise slidably engaging and disengaging diametrically opposite points on the arcuate or spherical member 13 that is mounted on the post 12'.

Since the contact-members 13 are of arcuate or spherical contour and the bars 25 have flatwise engagement therewith, there ensues a substantially point contact between the members 13 and 25, which, as has been said, provides a highly efficient electrical joint connection.

For furthering or increasing the efficiency of the contact between the members 13 and 25, each of the members 25 is provided, at or adjacent its respective opposite ends, with a surface coating or with an inserted plug 26 of highly conductive material, as silver or the like, disposed in the path of contact of the bar 25 with the spherical member 13, and, since the latter is likewise coated with a silver plating or the like, the contact resistance is, therefore, reduced to a minimum.

However, a point contact joint of this kind must be accompanied by pressure for realizing its best effects. Accordingly, at the hinged end of the pair of bars 25, there is provided on the respective opposite ends of the pintle 19 a pair of spring-cup washers 27 for bearing on the respective flat outer faces of the bars 25, suitable nuts or similar screw members 28 being threaded on the respective outer ends of the pintle 19 for drawing the washers 27 into compressive bearing upon the bars 25, whereby, in turn, the latter may, with ease and facility, be tensionally biased or adjustably compressed upon the contact-member 13 on the post 12.

At the same time, the employment of a pair of the bars 25, each taking half the current from or to the respective members 13, provides twice the thermal radiating surface that would be provided by a single blade type of switch of the same current rating, whereby it readily becomes possible, as I have done, to employ a point contact under pressure without appreciable rise in temperature of the switch structure and makes it highly feasible and practicable to employ such a switch successfully in indoor service.

At the swingable end of the pair of bars 25, there is provided a transverse pin 29, likewise

equipped with cup-washers 27 and co-operating nuts 28, whereby the bars 25 may likewise be more or less or adjustably drawn together for effecting pressure contact thereon upon the member 13 on the post 12'. 5

The pin 29, in addition, serves as the fulcrum point for the latching mechanism of the switch A, which includes a U-shaped bracket 30 disposed in horizontal outwardly open position between the free ends of the bars 25. The bracket 30, at each of its legs or ears is registrably apertured to receive the pin 29 and is further provided with a pair of small apertures 31 for reception of corresponding positioning pins 32 projecting from the inner face of the abutting bar 25. 10

The bracket 30, at the upper margin of its bight or transverse portion is forwardly extended or flanged to provide a ledge or stop-member 33, between which and the adjacent legs of the bracket 20 30 are slots 34 for the reception of respective bills 35 projecting rearwardly from the upper margin of filler-plates 36 disposed flatwise with respect to the legs of the bracket and also apertured, as shown, for the pin 29 and positioning pins 32. 15

The latch members proper comprise a pair of reversible companion bell-cranks 37, 38, each including a normally forwardly extending leg equipped with a bowed handle 39, and a more or less normally vertically disposed leg 40 having a rearwardly extending lug or spring support 41, the cranks 37, 38, being pivotally mounted on the pin 29 in reversed, interfitting relationship after the manner of a pair of scissors, that is to say, the cranks 37, 38, are of substantially similar contour and of full width throughout their extent, except at their hub, as at 37', and again at their respective free ends, as at 38', for permitting such nested or interfitting relationship, 40 the handle-members 39 being adapted to overlap each other at all times, so that a well defined but expansible eye or aperture, as at 42, is formed therebetween for entry of a hook-stick (not shown), for operating the latch in the customary manner, the overlapping relationship of the members 39, however, acting to preserve the continuity of the walls of the expansible eye 42 for preventing accidental dislodgement of the hook-stick therefrom, as best seen in Figures 3 and 9. 45

50 A tensional member in the form of a coil spring 43 is suitably engaged between the lugs 41 for normally biasing the handle-members 39 one toward the other into closed position, and the cutaway portions 37' at the hub provide a stop 55 44 of suitable shape for limiting the contrary relative opening movement of the cranks 37, 38, one from the other, the lug 41 of the crank 38 also having a stop-shoulder 45, for a purpose shortly appearing.

60 Additionally, the leg 40 of the crank 37 is equipped with a depending latch-arm 46 having a rearwardly turned catch or bill 47, which, when the bars 25 are engaged with the contact-members 13, is adapted, under bias of the spring 43, to snap under and latchingly engage the detent or bill 23 of the latch-post 20 for releasably retaining the switch A in closed position, the shoulder 45 on the lug 41 of the crank 38 meanwhile abutting the stop 33 of the mounting bracket 30. 70

In use and operation, the switch being in closed position as in Figures 1 and 2, a hook-stick of the customary form is thrust into the latch handle opening 42, and a pull is exerted on the handle 39 of the latch-crank 37, causing the same

to rotatively shift on the pin 29 until the crank 37 engages the stop 44 on the crank 38 for releasing the bill 47 from the latch-post 20, whereupon the members 25 may be swung upwardly and away, and for disengagement, from the contact-member 13 on the post 12', as shown in Figure 3, for rupturing or breaking the circuit with which the switch A is associated, the members 25 preferably being swung to a right angular position, as shown by dot-dash lines in Figure 2. 10

Not merely the latch mechanism, however, but also the switch-structure as a whole, is characterized by the ease and facility with which repairs may be made and the manner in which the maintenance of the switch may be effected in a simple and facile manner. 15

For example, those parts of the switch which are mounted on the plates 3, 4, may readily be removed therefrom without dismantling the supporting structure of the switch or disassembling the same from the bus-bars to which they are connected; even so, the plates 3, 4, may readily be removed and replaced without destroying the efficiency of the joint connection between the plates and the busses. 20 25

Likewise, new bars 25 may be installed, and the bars or members 13 may be removed and replaced, without impairing the current carrying capacities of the switch, and, in general, the entire switch structure possesses a high degree of 30 accessibility and ease of replacement of its several parts greatly conducive to the economical use thereof. 35

For closing the switch A, the hook-stick is again inserted in the aperture 42 and engaged with the crank 38 for pushing the bars 25 until the members 25 rest on the lugs 24 of the latch-post 20 and are again disposed in engagement with the contact-member 13 on the post 12', the bill 47 of the crank 37 meanwhile riding over the bill 23 of the latch-post for, as has been said, latching the switch A in closed position, as shown by Figure 2. 40

It will be seen that the latch mechanism of the switch comprises relatively few parts, the cranks 37, 38, being made or constructed from merely a single pattern, if desired, and therefore inexpensively produced. The simple and rugged construction favors a minimum maintenance attention and expense, and repairs, when necessary, 50 may be effected with facility and dispatch. 45

As has been said, for aiding in reducing the resistance losses at the point contact between the arms 25 and the contact-members 13, the latter are preferably surface-plated with a silver coating. As an alternate, the contact-members 13 may be provided with a circumferential inserted collar 48, as shown in the contact-member 13a of Figure 6, or with a circumferentially spaced series of diametrically opposite pairs of silver-plugs or the like 49, as in the contact-member 13b of Figure 7. 55 60

Again, for increasing the amperage of the switch, the contact-supporting post, as 12a, may be modified to permit the mounting thereon of two or more segmental spherical members, as, for example, the members 13, 13c, of Figure 8, the swingable bars of the switch (not shown), then being suitably widened, and their cross-sectional area correspondingly enlarged, for simultaneously engaging the pair of contact-members 13, 13c, when the switch is in closed position. 65 70

As a result of repeated operations of the switch A, wear will, of course, occur in the stationary 75

contact-members through the sliding engagement therewith of the bars 25. When wear becomes excessive, the efficiency of the contact between the contact-members 13 and 25 may be 5 readily restored by simply loosening the screws 15, which will permit rotative shifting of the stationary contact-members until an unworn surface is presented to the members 25, the stationary contact-members being then rigidly positioned on their respective supporting posts by a 10 tightening of the screws 15.

The same procedure may be easily followed in the case of the contact-members 13a and 13c, while, in the case of the contact-member 13b, it 15 will be obvious that, by sufficiently rotating the member, successive diametrical pairs of the inserts 49 may be selectively presented to the members 25 from time to time, as circumstances may require.

20 In the bar member 25, also, the silver inserts 26 may take various forms, more especially in the respect that such plugs 26 may be provided on both sides of the bar 25, as at 26a in Figure 13; again, instead of the plug form of insert, a 25 silver disc 26b may be plated, welded, or otherwise fixed on one or both sides of the bar 25, or a silver rivet, having flattened heads, as at 26c in Figure 13, may be provided, as may best serve the intended purpose, all such several forms of 30 silver contact-surfaces permitting the mere reversal of the bar 25 for restoring the efficiency of the contact surface when the same is impaired by wear.

In Figure 10 is illustrated a modified form of 35 double throw switch A'. In its essential details, the switch A' embodies the same elements as the switch A, with the addition, however, as is shown, of a third contact-supporting post 12b, contact-member 13c, and latch-post 20'.

40 The latch mechanism in the switch A' is composed of two of the cranks 37, so that, in either of the opposite positions of the swingable contact-member, a latch-arm 46 will be available for latching engagement with the corresponding 45 latch-post. Though not specifically here shown, it will be understood that the stop 30 of the latch-brackets is eliminated to permit unlatching movement of either of the cranks 37 as occasion may require.

50 Also the bars 25' constituting the swingable contact-member are each provided with an additional silver contact 26', in order that the bars 25' may have engagement with the stationary contact-member 13 adjacent the hinge pin 19 of 55 the switch in either of the alternate positions thereof.

The use and operation of the switch A' is, with 60 obvious modifications, substantially similar to that of the switch A.

60 In Figure 11 is illustrated a so-called double switch, that is to say, a switch including duplicate pairs of switch elements or bars 25'', each generally similar to the bars 25 of the switch A, the pairs of bars 25'' being mounted side by side 65 for parallel connection in an electrical circuit for affording a switch A' of twice the current carrying capacity of the switch A.

In this case, the switch construction is modified in an obvious manner to provide merely a 70 single latch-post, not indicated, but similar to the latch post 20 of the switch A. Merely one bracket 30 and pair of fillers 36 are employed and are disposed intermediate the inner opposing bars of the respective pairs of bars 25'' of the switch structure.

For such purpose, the pins 29 of the switch A are here replaced by an elongated pin 29', which extends through all four of the bars 25'', and a 10 filler block 50 is mounted on the pin 29' between each pair of the bars 25''. Spring washers 27 5 are mounted against the outer faces of the outer bars 25'', as in the switch A, but the other washers 27 are disposed against the inside face of the inner bars 25'', as will be readily seen by an inspection of Figure 10.

The switch A'' is, likewise, in use and operation, substantially similar to the switch A, hereinbefore described.

A so-called air-break horn-gap type of switch A''', suitable for use as an outdoor disconnecting 15 switch, is shown in Figure 12. Switches of such type are commonly mounted in elevated positions and are operated from the ground for disconnecting the line while under potential, while indoor disconnecting switches, as on switchboards and the like, are commonly protected by oil-switches or similar devices and are not opened or closed when under line potential.

20 My new switch construction is particularly adapted for cutting out a line when under potential, especially, as has been said, in outdoor service. As here shown, the switch A''' comprises three spaced insulator-stands 51, 52, 53, mounted on a suitable base, not shown, but as will be 25 readily understood by those familiar with the art.

The insulator 51 is the rotor stand and carries the rotor bearing 54 in which turns the customary operator-shaft which is, as has been said, commonly operated from the ground and serves to rotate the operator crank 55, the latter, in turn, 35 through a link 56, being connected to a bracket 57 mounted between the bars 25''' of the switch A''', which bars 25''' correspond in all essential details to the bars 25 of the switch A.

40 The stand 52 carries the hinge structure of the switch. The terminal plate 3', in this instance, extends from the stand 52 to and over the stand 51, and at its extreme end is formed with the terminal portion 6, as hereinbefore described. Similarly, the plate 3' carries the 45 terminal post 12 with its ball-contact 13 and the hinge-post 16, with its pintle 19, on which the bars 25''' are pivotally mounted, all, together with their appurtenant members, being 50 similar in form and function to the like elements or members of the switch A.

The stand 53 supports the plate 4', with its extension 6 and supported contact-post 12, ball 13, and associate parts, but in place of the latch-post of the switch A, there is mounted on the 55 plate 4' an upstanding stationary arcing horn 58.

On the swingable end of, and between, the bars 25''', there is mounted a block 59 carrying a so-called movable arcing horn 60 adapted for co-operation with the horn 58 for breaking the 60 arc when the switch is opened, as is usual in such installations.

In use and operation, the switch A''' does not depart materially from that of the usual form of air break horn-gap switch. It is to be particularly pointed out, however, that my switch construction is highly advantageous in service, inasmuch as, firstly, the need of pigtailed or flexible leads is entirely eliminated, and, secondly, the wiping contacts between the ball 13 and the 70 pair of bars 25''' at both ends thereof serve to preserve and maintain the cleanliness and effectiveness of the electrical joints made thereby, thus avoiding, also, the need of sleet-hoods and the like.

It may be added that the respective bars 25 are preferably formed, as best seen in Figures 3 and 5, upon their inner face with oppositely disposed arcuate slots or ways, as at 75, opening upon a side edge of the blade and leading to the respective inserts 26 for facilitating non-resistant electrical connection between the bars 25 and contact-members 13, and it will be understood that changes and modifications in the form, construction, arrangement, and combination of the several parts of my switch construction may be made and substituted for those herein shown and described without departing from the nature and principle of my invention.

15 Having thus described my invention, what I claim and desire to secure by Letters Patent is:

1. In an electrical switch, in combination, a spherical contact-member having a low resistance conducting surface coating, a second contact-member comprising spaced rigid blades for embracing the spherical member, the blades being each provided with an inwardly presented arcuate recess open at its lower end, and low resistance conducting elements mounted on the blades at the upper end of the respective recesses for electrically engaging the surface coated spherical member.

2. In an electrical switch, in combination, a pair of spaced upstanding posts, spherical contact-members mounted on the respective posts, a third contact-member comprising spaced rigid cross-pin connected blades for electrically connecting the spherical contact-members, one of said pins having engagement with one of said posts for pivotal movement of said blades, and means including spring-washers on the pins for adjustably effecting pressure-engagement of the blades on the spherical contact-members.

3. An electrical switch comprising, in combination, a pair of spaced companion base-members, upstanding posts mounted on the respective base-members, contact-members mounted upon, and at the upper extremity of said posts, a third post mounted on one of said base-members intermediate the first posts and their said supported contact-members, and a co-operable third contact-member comprising a pair of spaced companion electrically conductive blades pivotally mounted on the intermediate post each being provided at its opposite ends with contact-plug members mounted therein and extending outwardly from the inwardly presented faces thereof for at its respective opposite ends embracingly engaging the first contact-members in substantially point-wise tangential electrical contact.

4. In an electrical switch, in combination, a pair of spaced contact posts, an intermediate post, a pair of parallel laterally spaced contact blades pivotally mounted intermediate adjacent an end on the intermediate post, and at their other end being connected, said blades each being provided along their inwardly presented faces with respectively juxtaposed recesses opening at one end upon an outer longitudinal margin of the blade, contact plug members mounted rigidly on the respective blades in and extending outwardly from said recesses, a fixed contact post mounted in the path of movement of the blades, and a spherical contact member mounted on the post for projecting disposition between the blades into substantially point-wise tangential engagement with said contact plug members when the blades are swung into contact forming position.

5. In an electrical switch, in combination, a

pair of spaced contact posts, an intermediate post, a pair of parallel laterally spaced contact blades pivotally mounted intermediate adjacent an end on the intermediate post, and at their other end being connected, said blades each being provided along their inwardly presented faces with respectively juxtaposed recesses opening at one end upon an outer longitudinal margin of the blade, juxtaposed contact plug members mounted on the respective blades in and projecting outwardly from said recesses, a fixed contact post mounted in the path of movement of the blades, and a spherical contact member mounted on the post for projecting disposition between the blades into substantially point-wise tangential engagement with said contact plug members when the blades are swung into contact forming position, said spherical member having a diametrical size greater than the distance between the opposed outwardly presented faces of the contact plugs whereby said contact plugs will be placed under substantially an axial pressure when in contact-forming position with the spherical member.

6. In an electrical switch, in combination, a pair of spaced contact posts, an intermediate post, a pair of parallel laterally spaced contact blades pivotally mounted adjacent an end on the intermediate post and at their other end being connected, and spherical contact members mounted on the contact posts for projecting disposition between the blades when the latter are swung into contact-forming position, said spherical contact members being sized for substantially point-wise tangential contact on their opposed faces with the respective adjacent faces of said switch blades.

7. In an electrical switch, in combination, a first stationary spherical contact, a second stationary spherical contact in spaced relation to the first contact, a hinge-post intermediate said contacts, a fulcrum-pin transversely disposed on the hinge-post, a movable contact member comprising spaced registering parallel flat blades pivotally mounted adjacent an end on the fulcrum-pin and disposed upon opposite sides of the hinge-post, and a second transverse pin connecting the blades adjacent their opposite end, said blades being adapted for slidably make-and-break point-engagement with the first contact at a point located outwardly of both said pins and with the second contact at a point intermediate said pins.

8. In an electrical switch, in combination, a first stationary contact, a second stationary contact in spaced relation to the first contact, a hinge-post intermediate said contacts, a fulcrum-pin transversely disposed on the hinge-post, a movable contact-member comprising spaced registering parallel blades pivotally mounted adjacent an end on the fulcrum-pin and disposed upon opposite sides of the hinge-post, and a second transverse pin connecting the blades adjacent their opposite end, said blades being adapted for make-and-break engagement with the first contact at a point located outwardly of both said pins and with the second contact at a point intermediate said pins.

9. In an electrical switch, in combination, a pair of spaced insulation supports, a first stationary spherical contact on the first support, a second stationary spherical contact on the second support, a hinge-post upstanding from the first support and disposed intermediate said contacts, a fulcrum-pin transversely disposed on the hinge-

- post, a movable contact member comprising spaced registering parallel flat blades pivotally mounted adjacent an end on the fulcrum-pin and disposed upon opposite sides of the hinge-
5 post, and a second transverse pin connecting the blades adjacent their opposite end, said blades being adapted for slidable make-and-break point-
engagement with the first contact at a point located outwardly of both said pins and with the
10 second contact at a point intermediate said pins.
10. In an electrical switch, in combination, spaced insulation supports, a first stationary spherical contact on the first support, a second stationary spherical contact on the second support, a hinge-post upstanding from the first support and disposed intermediate said contacts, a fulcrum-pin transversely disposed on the hinge-
15 post, a movable contact member comprising spaced registering parallel flat blades pivotally mounted adjacent an end on the fulcrum-pin and disposed upon opposite sides of the hinge-
20 post, a second transverse pin connecting the blades adjacent their opposite end, said blades being adapted for slidable make-and-break point-
25 engagement with the first contact at a point located outwardly of both said pins and with

the second contact at a point intermediate said pins, and co-operable latch-members on the movable contact-member and on the second support for releasably securing the contact member in circuit-closing engagement with said contacts. 5

11. In an electrical switch, in combination, spaced insulation supports, a first stationary spherical contact on the first support, a second stationary spherical contact on the second support, a hinge-post upstanding from the first support and disposed intermediate said contacts, a fulcrum-pin transversely disposed on the hinge-
10 post, a movable contact member comprising spaced registering parallel flat blades pivotally mounted adjacent an end on the fulcrum-pin 15 and disposed upon opposite sides of the hinge-
post, a second transverse pin connecting the blades adjacent their opposite end, said blades being adapted for slidable make-and-break point-
15 engagement with the first contact at a point located outwardly of both said pins and with the second contact at a point intermediate said pins, and means co-operable with said pins for adjust-
20 ably effecting pressure engagement of the blades on the embraced spherical contact members. 25

WILLIAM H. LINDAE.
